A. SUNDH.

ALTERNATING CURRENT BRAKE MAGNET APPARATUS.

APPLICATION FILED OCT. 9, 1906.

1,031,743.

Patented July 9, 1912.

UNITED STATES PATENT OFFICE.

AUGUST SUNDH, OF YONKERS, NEW YORK, ASSIGNOR TO OTIS ELEVATOR COMPANY, OF JERSEY CITY, NEW JERSEY, A CORPORATION OF NEW JERSEY.

ALTERNATING-CURRENT-BRAKE-MAGNET APPARATUS.

1,031,743.

Specification of Letters Patent.

Patented July 9, 1912.

Application filed October 9, 1905. Serial No. 281,922.

To all whom it may concern:

Be it known that I, AUGUST SUNDH, a citizen of the United States, and residing at Yonkers, in the county of Westchester and State of New York, have invented a new and useful Improvement in Alternating-Current-Brake-Magnet Apparatus, of which the following is a specification.

My invention relates to brakes, and one of its objects is the provision of simple and efficient means for retarding or checking the movement of the armature of an alternating current electro-magnet, which may be used for releasing brake-applying means.

More particularly it is the object of the present invention to combine a dash-pot with an electro-magnet which is operated by alternating or pulsating currents to effect the release of brake-applying means.

Other objects of my invention will appear hereinafter, the novel combinations of elements being pointed out in claims.

In the accompanying drawings, Figure 1 represents an elevational view of a brake and means for operating the same; and Fig. 2 is a vertical sectional elevational view taken at right angles to Fig. 1 on the line *a*, *a*.

1 designates a box or casing mounted on the bed-plate 2 and inclosing the brake-applying means. On the upper portion of the casing is secured a yoke 3, to which is secured the electro-magnet 4. This electro-magnet may be any suitable alternating current electro-magnet, such as disclosed, for example, in the patent to Lindquist, 764608, July 12th, 1904, electro-magnet, or in the patent to Lindquist, 744733, November 24th, 1903, electro-magnet.

The upper portion of the yoke 3 is extended into a cup 5, the purpose of which will be explained hereinafter. To the upper central portion of the yoke 3 is secured a sleeve 6, such sleeve being in this instance screw threaded into the yoke, and prevented from rotation by a set screw 7, after said sleeve has been placed in such position as to form a flat bottom 8 for the cup 5. On the under side of the upper portion of the yoke 3, and screw threaded on the sleeve 6, is a frame 9 to which are secured laminated poles 10 by means of pins 11, 11' which are preferably composed of wood fiber. Se-

cured to the lower portion of the fixed poles 10, are the electro-magnet spools or solenoids 12 and 12'. Said poles project half way into said solenoids, which are held in place on the downwardly projecting sleeve 14 by means of a nut 13. The armature comprises a plurality of laminated projections corresponding to the poles 10, 10' and secured to the sleeve 18 by means of pins 17 and 17' which are driven through the armature frame 16, the projections 15, and part way into the armature sleeve 18. The sleeve 18 is provided with a central longitudinal screw-threaded hole 19, through which is extended the screw-threaded portion 20 of the rod 21. After the armature is adjusted in position so that the projections 15, 15' may enter the various spools 12, 12', the nut 23 is tightened and locked into position by the nut 24.

The rod 21 extends upwardly through the longitudinal hole 22 of the electromagnet sleeve 6, and is adapted to move freely therein. The screw-threaded portion 20 of the rod 21 is extended downwardly into a cup 26 which has a downward projection 27. Pivoted to this projection at 28 is a vertical rod 29 which is provided with an enlarged screw-threaded portion 30, on which is placed a combined nut and brake spring holding means 31. The tension of the brake spring 32 may be adjusted by means of said nut 31, and after said adjustment is made the nut 31 may be locked in position by the lock nut 37, the latter being retained in place between the annular recesses 35 and 36 of the yoke 3, and the upper portion of the casing 1, respectively.

The lower portion 29' of the rod 29 is pivoted at 38 to the bell-crank lever 40 which is pivoted at 41 to the standard 39, secured to the base plate 2. The arm 70 of the bell-crank lever 40 extends outwardly through an opening in the casing 1, and has pivoted to it at 42 a link 43, which is pivoted at 49 to an additional bell-crank lever 44. The last named bell-crank lever is pivoted at 46 to the standard 45, and also secured to the base plate 2. The respective arms of the bell-crank lever 44 are pivoted at 47 and 49 to the brake bands 48 and 50, whose other ends are pivoted at 51 to a standard 52.

53 designates a brake pulley to which the
brake bands 48 and 50 are applied, said
brake pulley being secured to the driving
shaft 54 of a motor, which may be used for
5 any purpose desired, for example, the oper-
ation of hoisting apparatus for elevator
cars.

The cup 5 at the upper portion of the
yoke 3 is provided with a substantially air-
10 tight cap 55, so as to have a chamber 71
which is entirely inclosed. Although the
rod 21 has a free movement in the hole 22
of the sleeve 6, it should fit therein prefer-
ably as nearly air-tight as practicable. In
15 order to secure such an air-tight fit a leather
washer or a stuffing box may be placed be-
tween the rod 21 and the sleeve 6, if desired.

The upper end of the rod 21 is shown as
screw-threaded at 59, and provided with a
20 shoulder 61. A cup-shaped piston 57 has
a central hole 58 which may be screw
threaded and fitted over the screw-threaded
portion 59, and secured rigidly in place
against the shoulder 61 by means of the
25 nut 60.

At 62 is a hole which affords communica-
tion between the under side and upper side
of the piston 57, but is normally closed by
means of the valve 63 which is held in closed
30 position by the spring 65. This spring is
held in place by means of a bolt 64, which is
secured rigidly to the upper side of the pis-
ton 57. The valve 63 is pivoted at 66 to the
frame 67 which may be secured in any suit-
35 able manner, as by means of the set screw
68, to the upper side of the piston 57.

When the electro-magnet is energized the
parts will assume the position shown in Fig.
2. The brake spring 32 will be compressed,
40 the rod 29 moved upwardly and the link 43
to the left, as viewed in Fig. 1, and conse-
quently the brake bands 48 and 50 moved
out of contact with the brake pulley 53.
Fig. 1, however, shows the brake applied.
45 When the electro-magnet is deenergized the
valve 63 will open automatically and allow
free downward movement of the piston 57,
and therefore a quick application of the
brake. Should the brake bands wear so
50 that the bottom of the piston 57 would strike
against the surface 8 when the brake is ap-
plied, the said piston 57 may be adjusted by
releasing the lock nut 25 and turning the
rod 21 so as to move the same upwardly to
55 the desired extent, and then again securing
the nut 25 in position against the upper por-
tion of the cup 26. In this case the nuts
23 and 24 will also have to be loosened so
that the rod 21 may be turned, and then
60 again secured in original position.

It has been found in practice that when
the alternating current magnet is energized,
the armature is drawn up too suddenly and
the brake released too quickly thus tending
65 to injure some of the parts by not giving

them time to acquire momentum. That is,
the tendency would be to jerk the various
elements apart by the very sudden or quick
movement of the armature when the electro-
magnet is energized with the alternating
70 current. Another serious objection to the
use of alternating current magnets is the
slamming of the pole faces together, which
is not only very noisy, but soon destroys the
magnets. It has been proposed to use
75 springs or other cushioning devices to pre-
vent this slamming, but such devices do not
prove entirely efficient, and are impractical,
as they prevent the magnet surfaces from
coming together, and thus cause a great
80 waste of current. It is therefore necessary
to have some retarding device to prevent
this sudden movement and obtain, on the
contrary, a gradual upward movement of
the armature to safely operate the brake-
85 releasing means. It should be noted that
in the operation of the device, that is, when
the electro-magnet is energized and the ar-
mature drawn upwardly, the valve 63 is au-
tomatically closed so as to form a cushion
90 of air in the chamber 71 on the upper side
of the piston 57. Furthermore, a partial
vacuum is formed on the under side of the
piston 57 which assists the effect of the air
cushion in checking or retarding the sudden
95 movement of the armature to its final at-
tracted position.

Instead of relying on the action of air or
a partial vacuum for retarding the upward
movement of the armature, the chamber 71
may be filled with a liquid such as oil, if de-
sired, and the valve 63 omitted and one or
more holes 62 of suitable size provided in
the bottom of the cup piston 57 to serve to
restrict the flow of the fluid from the upper
105 side to the lower side of said piston. Or in
addition to the restricted passages, a valve
opening upwardly may be provided so that
the piston may have a quick downward
movement. Or the piston 57 may have no
110 restricted passages or no valves at all, but
fit so loosely in the cup 50 as to allow a
liquid to flow around the same from the
upper to the lower side and vice versa, in
which case the sudden upward movement of
115 the armature will also be checked and re-
tarded.

Although I have herein shown only one
form of the embodiment of my invention, it
is obvious that various changes in the de-
120 tails of construction and arrangement of
parts may occur to and be made by those
skilled in the art, without departing from
the spirit and scope of my invention. I
therefore do not wish to be limited strictly
125 to the construction herein described and
shown.

What I claim and desire to have protected
by Letters Patent of the United States, is:—

1. The combination with an alternating
130

current magnet, of an armature connected to the parts to be actuated, a cup piston connected rigidly with said armature, and a substantially air-tight casing wholly inclosing said piston.

2. The combination with an alternating current magnet, of a supporting yoke therefor, a cylindrical cup on the upper portion of said yoke, an armature, a piston connected to said armature and movable in said cup, and a substantially air-tight cap for said cup.

3. The combination with an alternating current magnet, of a supporting yoke therefor, a cylindrical cup formed integral with said yoke, an armature, a piston rigidly connected to said armature and movable in said

cup, and a cap forming with said cup an air-tight closure.

4. The combination with an alternating current magnet, of a supporting frame therefor, a cylindrical cup carried by said frame, a cap for the cup forming therewith an air-tight closure, a piston adapted to reciprocate in said cup, a check valve in said piston, and an armature for the magnet connected to the piston.

In testimony whereof, I have signed my name to this specification in the presence of two subscribing witnesses.

AUGUST SUNDH.
